UNITED STATES PATENT OFFICE.

WILLIAM C. SHARPLESS, OF PHILADELPHIA, PENNSYLVANIA, ASSIGNOR TO HIMSELF AND DAVID H. WATTS, OF SAME PLACE.

TILE-LINED STRUCTURE.

SPECIFICATION forming part of Letters Patent No. 337,629, dated March 9, 1886.

Application filed August 15, 1885. Serial No. 174,471. (No model.)

To all whom it may concern:

Be it known that I, WILLIAM C. SHARPLESS, a citizen of the United States, residing in Philadelphia, Pennsylvania, have invented 5 certain Improvements in Tile-Lined Structures, of which the following is a specification.

The object of my invention is to construct a strong and durable tile-lined tub, tank, vat, 10 or like structure, and this object I attain in the manner which I will now proceed to describe, reference being had to the accompanying drawings, in which—

Figure 1 is a perspective view of the outer 15 shell or casing of the structure; Fig. 2, a sectional perspective view, on a larger scale than Fig. 1, of part of the structure with the tile-lining applied thereto; Fig. 3, a transverse section of the structure on a still larger scale, 20 and Fig. 4 a longitudinal section.

The shell or casing of the structure is composed of the side plates, A A, end plates, B B, and bottom plate, D, the side and end plates being provided at the ends with flanges d, 25 whereby they may be readily secured together by bolts or rivets, and both side and end plates having at or near the bottom internal flanges, a, bolted, riveted, or otherwise secured to the bottom plate, D, so that a perfectly rigid and 30 water-tight structure is produced. To the inside of the shell or casing thus constructed I apply a layer, f, of cement, to which are secured the tiles F, forming the lining of the structure. The upper edges of the top row of 35 tiles are covered and protected by an internal flange, g, on the side and end plates of the casing.

The plates composing the shell are preferably of cast-iron, for the reason that the cement

used for securing the tiles takes a much firmer 40 hold upon this metal than upon any other, and a cast-iron plate is cheaper than a wrought-iron plate, which would have to be provided with barbs or recesses to retain the cement.

The making of the shell of a number of 45 separate plates is much preferable to the casting of said shell in one piece, as, owing to the large size of the shell and the thinness of the metal composing the same the tendency of the shell to warp and twist when made in one 50 piece renders this method of manufacture extremely difficult and expensive.

Tiles may be applied to the outside of the shell or casing as well as to the inside, if desired, the side and end plates of the shell having at the top external flanges for protecting 55 the top row of the outside tiling.

I claim as my invention—

1. The within-described structure, consisting of an outer metallic shell composed of side, 60 end, and bottom plates secured together at the corners and having a lining of tiles cemented thereto, all substantially as specified.

2. The within-described structure, consisting of an outer shell composed of side, end, 65 and bottom plates of cast-iron having flanges cast therewith, by which the plates are secured together at the corners, and having a lining of tiles cemented directly to the inner faces of the plates, all substantially as specified. 70

In testimony whereof I have signed my name to this specification in the presence of two subscribing witnesses.

WM. C. SHARPLESS.
